CLAIM

We claim the ornamental design for a foot pad of an exercise device, as shown and described.

DESCRIPTION

FIG. 1 a side, top perspective view of a foot pad of an exercise device;

FIG. 2 is a close-up, perspective view of the foot pad of the exercise device of FIG. 1; and,

FIG. 3 is a top plan view of the foot pad of the exercise device of FIG. 2.

The ornamental design that is claimed is shown in solid lines in the drawings. The evenly spaced broken lines shown in the figures are for the purpose of showing environment and form no part of the claimed design.
